UNITED STATES PATENT OFFICE.

JOHN J. SNYDER, OF DENVER, COLORADO, ASSIGNEE TO THE STANDARD GAS LAMP COMPANY, OF CHICAGO, ILLINOIS.

INCANDESCENT VAPOR-BURNER.

SPECIFICATION forming part of Letters Patent No. 650,735, dated May 29, 1900.

Application filed July 1, 1899. Serial No. 722,588. (No model.)

To all whom it may concern:

Be it known that I, JOHN J. SNYDER, a citizen of the United States, residing at Denver, in the county of Arapahoe and State of Colorado, have invented new and useful Improvements in Gas-Generating Gas-Fixtures, of which the following is a specification.

My invention relates to gas-generating gas-fixtures, and contemplates the provision of a fixture which is at once simple and inexpensive in construction and efficient and reliable in operation and is calculated to afford a steady light when the temperature is very low, as well as when it is normal and high.

The invention is possessed of many advantageous features other than those mentioned and will be fully understood from the following description and claims when taken in conjunction with the accompanying drawings, in which—

Figure 1 is an elevation, partly in section, illustrating my improved fixture. Fig. 2 is an enlarged vertical section of the burner of the fixture. Fig. 3 is a detail section of the burner, taken in a plane at right angles to Fig. 2. Fig. 4 is a transverse section taken in the plane of line 4 4 of Fig. 3. Fig. 5 is a detail perspective view showing the generator and its appurtenances. Fig. 6 is a detail vertical section of the generator. Fig. 7 is a perspective view of the generator-protector, which has for its purpose to hold cold air away from the generator. Fig. 8 is a detail diametrical section of a modification, and Figs. 9 and 10 are elevations of cleaning instruments used in conjunction with the fixture.

Referring by letter to the said drawings, and more particularly to Figs. 1 to 7 thereof, A is a reservoir for gasolene or other hydrocarbon suitable for consumption in my fixture.

B is a burner, and C is a tube which serves to convey hydrocarbon from the reservoir to the burner. The said tube extends through the vertical center of the reservoir and the interiors of the two are connected by a port a in the tube. At about the distance shown below the reservoir the tube is made to describe a right-hand curve b, and is then carried laterally and horizontally to the burner B, while above the reservoir said tube is

threaded for the connection of a hanger D. This hanger is preferably cast in one piece and is carried toward the left from the tube C and is preferably provided with a loop c. 55 The upper end or bearing-point d of the hanger may be a hook, as shown, when an eye e on a wall or other support is to be engaged, or it may be an eye when a hook on a support is to be engaged, as desired. The bearing-point d of the hanger is arranged coincident with the vertical center of the fixture. By virtue of this and the arrangement of the reservoir A on tube C and the curve b of said tube C the upper portion of the tube and the 60 burner B will always rest in a vertical position, irrespective of the quantity of hydrocarbon contained in the reservoir A, which is an important advantage. The tube C terminates in a vertical portion f, which is let 65 into a threaded port g in the generator E of the burner.

The generator, which constitutes one of the important features of my invention, is cast in one piece, and in the preferred embodiment 75 of the invention is annular in form or otherwise shaped to afford a central passage g' through it, and is provided with a lateral horizontal flange h, and also with a threaded port i, the latter being for the connection of a tube 80 j, which is provided with the usual projector k and valve l for controlling the supply of gas to the injector.

In the main or annular portion of the generator a generating-canal F is drilled or otherwise formed, the said canal, which is preferably of an inverted-V shape, connecting at its ends with the ports g i and having its middle or apex arranged close to the upper end of the generator, where the hydrocarbon there- 85 in will be subjected to the white heat of the mantle G, the lower part of which surrounds the generator and is connected to a support l' rising from the same, as shown. In casting the generator there is sufficient metal left 90 at the outer side of its upper portion (see m' in Fig. 5) to drill the generating-canal F through, the canal being drilled from i and g and connecting at the apex close to the upper rim of the generator, as shown in Fig. 6. This 95 metal projects slightly, as shown, but does not interfere with the lower portion of the 100

mantle fitting down over the generator. By this method of construction a generator is produced in which the generating-canal is brought up in close proximity to the white heat of the mantle and is separated from said mantle by but a minimum amount of metal, and at the same time a generator which is formed in one piece and not in two sections and in which the generating-canal is easily accessible to the cleaning-wire H.

The generator is further provided with two notches m, the same being formed in its upper end at opposite sides of the apex or middle of the canal F and having for their purpose to promote the passage of the heat of the incandescent mantle to the said canal F. When the lamp is in operation, the gas escapes through said notches and extends the incandescent heat of the mantle at that point downward to within about one-sixteenth of an inch from the apex of the canal F, thus greatly promoting the heat of the generating-canal F, which is an important advantage.

The generator is advantageous because of the facility with which it may be cleared throughout its length of the sediment deposited through the hydrocarbon, it being simply necessary when the generator is to be cleared to disconnect the tubes f, j, remove the generator from the burner, invert it, and work an instrument H (see Fig. 9) in the arms of the canal F, and then hold the burner so as to permit the loosened sediment to drop from the canal.

I is the usual wire-gauze diaphragm, which is seated in an inner rabbet at the upper end of the generator E and above the passage g' thereof.

J is a tube which is connected to the generator E and is designed to receive gas from the injector k and convey it to the space within the said generator. This tube is of course arranged a sufficient distance above the injector to permit of a suitable quantity of air being commingled with the gas before it reaches the point of ignition.

K is the jacket of the burner, which is detachably connected by screws n to lugs p on the flange h of the generator E. This jacket is provided below the generator with an opening q, normally closed by a vertically-sliding door r, the purpose of which opening is to permit of the introduction of an instrument L, such as shown in Fig. 10, to clear the minute aperture of the injector k when the same is partially or wholly obstructed by sediment. By virtue of this the aperture of the injector may be cleared so quickly that while the light will be extinguished by the insertion of the instrument L the generator E will not have time to cool, and hence when the cleaning is effected the burner may be again lighted by simply holding a match above the chimney, presently described.

5 The jacket K is extended about the proportional distance illustrated above the flange h

of the generator and is provided at its upper end with an inwardly and upwardly directed flange s, which serves, in conjunction with a rim t, mounted on uprights u, rising from the jacket, to hold a chimney L². The construction described precludes the use of any but a chimney of small diameter, which is advantageous, because it insures a swift draft and perfect combustion, and hence the maintenance of a strong and steady light. The draft of air is admitted to the chimney L² through openings v, formed in the jacket K, adjacent to the upper end thereof, as illustrated.

When desired, in lieu of providing the jacket K with draft-openings v a perforated gallery L' may be employed to supply air to the chimney and support said chimney, the said gallery being removably held on the jacket by frictional contact. When the gallery L' is employed, the jacket does not extend so far up as in Fig. 2, and in all cases the lower end of the chimney is but a very slight distance below the incandescent heat. As a result of this the chimney is uniformly heated from top to bottom and is not liable to break, which renders the employment of the advantageous small chimney practical. As will be readily observed, the jacket alone or in conjunction with the gallery L' constitutes a burner-casing.

In order to prevent the current of air entering through the apertures v from cooling the generator, and thereby retarding the generation of gas and diminishing the light, I provide a protector M, the purpose of which is to hold such airway from the generator without interfering with its passage to the mantle. This protector M is preferably in the form of a ring, which is split, as shown, so as to accommodate itself to the mantle-support l', and is placed around the main portion of the generator and held at the proper distance therefrom by suitable lugs w, formed integral with the generator.

Many of the so-called "lower-generator" fixtures are efficient and afford a good light when the temperature is normal or high; but when the temperature is low the air entering the chimney to support combustion acts against and keeps the generator cool, with the result that the generation of gas is retarded and but a poor unsteady light afforded.

My improved protector M effectually prevents the air entering the chimney from acting against the generator, and hence it insures a perfect generation of gas and the production of a strong and steady light, irrespective of the temperature in which the fixture is operated.

The protector M is made in the manner described in order to facilitate its removal when desired, but may be of any other construction calculated to enable it to perform the function stated.

At its lower end the jacket K has a removable foraminated portion N, which serves

to enhance the appearance of the burner and hide the same from view. This removable portion, which is normally held by frictional contact on the lower end of the jacket, is 5 provided with a notch *x* for the passage of the valve-stem *l* and a slot *v* for the passage of the tube *C*. It is designed to be disconnected from the jacket *K* and moved back out of the way on the horizontal portion of the 10 tube *C* when it is desired for any purpose to gain access to the interior of the burner.

In starting my improved lamp the jacket portion *N* is moved back on the tube *C*, as stated, and an alcohol torch or the like is held 15 under the tube *j*, and when this is done the hydrocarbon as it is expended or converted into vapor or gas passes up the arm of the generating-canal *F* past its apex and down the canal, where it communicates with the 20 port *g*. When sufficient gas is thus generated, the valve *l* is opened and the fixture lighted by a match or the like held at the top of the chimney. The fixture will remain lighted so long as the valve is left open and 25 the supply of hydrocarbon lasts, the heat of the incandescent mantle serving to maintain the generation of gas in the generator.

Having thus fully described my invention, I claim—

- 30 1. In a gas-generating gas-fixture, a generator formed in one piece and provided with a vertical passage and notches in its upper end and also provided with a generating-canal having an intermediate portion of its 35 length disposed adjacent to the upper end of the generator and arranged between the notches in said end; in combination with a hydrocarbon-tube and an injector-tube connected with the generator and communicating with the canal thereof, and a mantle surrounding the generator, substantially as specified.
- 40 2. In a gas-generating gas-fixture, a generator formed in one piece and having the offset portion *m*⁷ at its outer side extending to a point adjacent to its upper end, and also having a central passage, and a generating-canal formed in the portion *m*⁷ and arranged with its intermediate portion adjacent to the 45 upper end of the generator; in combination with a hydrocarbon-supply tube and an injector-tube connected with the generator and communicating with the canal thereof, substantially as specified.
- 50 3. In a gas-generating gas-fixture, a generator provided with a vertical passage and notches in its upper end and also provided with an inverted-V-shaped generating-canal having an intermediate portion of its length 55 disposed adjacent to the upper end of the generator and between the notches therein,

in combination with a mantle surrounding the generator, substantially as specified.

4. A gas-generating gas-fixture having a chimney and one or more openings for the admission of air to support combustion, and also having a generator containing a generating-canal and provided with exterior lugs, and a protector surrounding the generator and the lugs thereof whereby an air-space is afforded between it and the generator entirely around the latter, substantially as specified. 65

5. In a gas-generating gas-fixture, a generator provided with a vertical passage and one or more notches in its upper end, and also provided with a generating-canal having an intermediate portion of its length disposed adjacent to the upper end of the generator and the notch or notches therein; in combination with a mantle surrounding the generator, substantially as specified. 75

6. A gas-generating gas-fixture having a chimney and one or more openings for the admission of air to support combustion, and also having a generator containing a generating-canal and provided with exterior lugs, a protector surrounding the generator and the lugs thereof whereby an air-space is afforded between it and the generator entirely around the latter, and a mantle surrounding the generator and interposed between said generator and the protector, substantially as specified. 85

7. A gas-generating gas-fixture comprising a burner-casing provided with one or more openings for the admission of air to support combustion, a chimney supported above said casing, a generator arranged in the casing and having a central passage and also having lugs *w*, a hydrocarbon-supply tube and an injector-tube connected with the generator, a mantle surrounding the generator, and a protector-ring surrounding the mantle and the lugs *w* of the generator and interposed between the mantle and the opening or openings in the burner-casing, substantially as specified. 95

8. In a gas-generating gas-fixture, the combination of a generator, an injector-tube and a hydrocarbon-supply tube connected with the generator, and a jacket surrounding the injector and hydrocarbon-supply tubes and having a lower removable portion provided with a slot loosely receiving the hydrocarbon-supply tube, substantially as specified. 105

In testimony whereof I have hereunto set my hand in presence of two subscribing witnesses. 115
